PICNIC TABLE

Glenn Offutt, Warren, and Warren Daum,
Niles, Ohio

Application October 17, 1949, Serial No. 5,536

Term of patent 14 years

(Cl. D33—14)

To all whom it may concern:

Be it known that we, Glenn Offutt and Warren Daum, each a citizen of the United States, residing at Warren and Niles, respectively, in the county of Trumbull, and the State of Ohio, have invented a new, original, and ornamental Design for a Picnic Table, of which the following is a specification, reference being had to the accompanying drawing, forming a part thereof.

The characteristic features of our design reside in the portions shown in full lines in the drawing.

We claim:

The ornamental design for a picnic table, substantially as shown and described.

GLENN OFFUTT.
WARREN DAUM.
